UNITED STATES PATENT OFFICE.

JAMES WARD AND RUFUS WASHBURN, OF HANDLEY, TEXAS.

SULKY-CARRIAGE FOR PLOWS.

SPECIFICATION forming part of Letters Patent No. 247,446, dated September 20, 1881.

Application filed January 26, 1880.

To all whom it may concern:

Be it known that we, JAMES WARD and RUFUS WASHBURN, of Handley, in the county of Tarrant and State of Texas, have invented 5 a new and valuable Improvement in Sulky-Carriages for Plows; and we do hereby declare that the following is a full, clear, and exact description of the construction and operation of the same, reference being had to the annexed drawings, making a part of this specification, and to the letters and figures of reference marked thereon.

The present invention relates to that class of sulky or wheel plows in which provision is 15 made for raising and lowering the plow and ground or transporting wheels.

The object of the invention is to furnish a sulky-frame and plow supporting and adjusting devices of a simplified construction, and 20 to provide more effective means for gaging the depth of the penetration of the plow into the ground, and guiding or steadyng the movement thereof. These objects we attain by the construction and combination of devices, which 25 will be hereinafter more fully described, and then set forth in the claim.

Figure 1 is a perspective view of a sulky-plow constructed according to our invention, the view being taken from the wheel side of 30 the frame. Fig. 2 is a perspective view taken from the plow side of the frame.

The frame-work of the plow-sulky consists of the parallel longitudinal bars A B and the front connecting-bars, C, forming a part of or 35 made in one piece with said parallel bars A B. A third bar, D, also extending in a length-wise direction on the outside of the bar B, has a front top plate, E, which serves to support the draft-tongue F. The plate E has a down- 40 wardly-projecting portion or plate, G, which fits against the inner side of the bar B, and is riveted or bolted to the same. The draft-tongue is pivoted to the under side of the plate E by means of a bolt, a, and is extended in 45 rear of the pivot and provided with a clamping-bolt or other device, d, which extends through a curved slot, e, made in the plate E. The object of this construction is to permit the draft-tongue to be shifted to the right or 50 left to take more or less land.

The plow-supporting yoke or hanger H is

fitted between the two bars B D of the sulky-frame, and turns at its front end upon a transverse bolt, I, passed through said bars, or else said bolt may turn with the hanger and move 55 in bearings in the bars B D. The beam J of any ordinary plow is connected with the hanger or yoke H by a transverse bolt or pin passing through said beam; or said beam can be connected with the hanger by means of a clip or 60 clamp device of any preferred construction. The plow-beam is free to turn in its supporting yoke or hanger, and has the customary clevis at its front end for the attachment of the draft.

The means for varying the depth of penetration of the plow into the ground or raising it above the same comprise the pivoted lever K, which is pivoted to the bar B of the sulky-frame, and provided with a rearwardly-extending arm, k, connected by means of a link, h, with the free or rear end of the plow-hanger or supporting-yoke. The lever K is slotted for the passage of a curved retaining-plate, L, the upper edge of which is notched. A locking pawl or dog, M, pivoted in the slotted portion of the lever K, engages with said notched plate L, and has an oblique slot, m, through which passes a pin on the lower end of a lever, N, that is connected with the main lever 80 K by a suitable fulcrum pin or connection. A spring, O, arranged between the two levers K N will serve to press the pawl or dog M into the notches of the plate L, so as to retain the plow-hanger in any position in which it may 85 be placed. By pressing upon the lever N the pin carried by the same will move in the oblique slot of the dog, so as to disengage the latter from the retaining-plate and permit the plow-beam to be raised or lowered to suit the 90 requirements of the case.

It will readily be observed that the arrangement of the plow-hanger between the two beams B D will serve to support and brace the same on both sides, so as to prevent any 95 lateral displacement thereof. The beam B extends beyond the landside of the plow, and has an outwardly-bent rear arm, B', in which is swiveled the arm or hanger P of a caster-wheel, Q. This wheel travels on the ground 100 directly in rear of the landside portion of the plow, and serves to take the weight thereof,

so as to make the draft lighter than if said wheel were not present.

R represents a ground or bearing wheel, which travels on the unplowed or unbroken ground, and its spindle or axle-arm is attached to the lower end of a lever, S, which is pivoted to the beam A of the sulky-frame. The lever S is slotted in the same manner as the lever K, and like the latter is provided with a locking-dog, T, which engages with the notched or rack plate U, and is connected with the spring-pressed disengaging-lever V. By shifting the position of the lever S the wheel R is raised or lowered, so as to adapt it to the varying positions of the plow. When the plow is raised above ground and the wheel R lowered to its full extent, it and the caster-wheel will enable it to be drawn from place to place.

20 The driver's seat V' is located in proper relation to the levers K S, so as to enable the same to be conveniently manipulated, and the arched supporting-bar W of said seat is secured to the bars A B of the sulky-frame. A foot board or support, X, is arranged between said bars and is secured to the same.

A frame constructed according to our invention is much lighter and stronger than others heretofore known, and our means used 30 in connection therewith for supporting the plow will tend to make up a sulky-plow which

possesses many advantages over existing plows of an analogous description.

We make no claim to broadness of invention, as we are well aware that many plows 35 are provided with plow-hangers and ground-wheels, the positions of which are controlled by levers and retaining devices for the latter; but

40 What we do claim as our invention, and desire to secure by Letters Patent, is—

In a sulky-plow, the combination of the longitudinal bar A, the transverse front bar, C, the longitudinal bar B, having rear outwardly-projecting arm, B', and caster-wheel Q, 45 mounted therein, the short longitudinal bar D, having a front plate, E, connected with the bar B, and the pivoted plow-hanger or yoke H, arranged between the bars B D, with the ground or bearing wheel, draft-tongue, and devices for raising and lowering the plow-hanger and bearing-wheel, as and for the purpose set forth.

In testimony that we claim the above we have hereunto subscribed our names in the presence 55 of two witnesses.

JAMES WARD.

RUFUS WASHBURN.
